UNITED STATES PATENT OFFICE.

FRANK C. ANDERSON, OF CINCINNATI, OHIO, ASSIGNOR OF ONE-HALF TO
AMERICAN VALVE AND METER COMPANY, OF CINCINNATI, OHIO, A
CORPORATION OF WEST VIRGINIA.

NUT-LOCK.

No. 796,691.

Specification of Letters Patent.

Patented Aug. 8, 1905.

Application filed March 9, 1903. Serial No. 146,950.

To all whom it may concern:

Be it known that I, FRANK C. ANDERSON, a citizen of the United States, residing at Cincinnati, in the county of Hamilton and State of Ohio, have invented certain new and useful Improvements in Nut-Locks, of which the following is a full, clear, and exact description, reference being had to the accompanying drawings, forming part of this specification.

My invention relates to improvements in nut-locks designed particularly for railway frogs and crossings, though equally capable of use on fish-plates for uniting the meeting ends of rails or in any other situations where jarrings or vibrations would tend to loosen the nuts; and it has for its object the provision of very simple, inexpensive, and efficient automatic means for locking the nuts when screwed up tight and without any possibility of their becoming accidentally loosened.

The novelty of my invention will be hereinafter more particularly set forth, and specifically pointed out in the claims.

In the accompanying drawings, Figure 1 is a sectional end elevation of a railway-rail with fish-plates or other plates applied thereto, with a connecting-bolt equipped with my improved nut-lock mechanism. Fig. 2 is a side elevation of Fig. 1 looking toward the left. Fig. 3 is a detached elevation of the nut-locking dog.

The same letters of reference are used to indicate identical parts in all the figures.

In the drawings an ordinary railway-rail is shown, of which A is the head, B the web, and C the foot.

D represents the plates, whether fish-plates or other plates, fitted to the web between the under side of the head and the upper side of the foot of the rail, and E is the connecting-bolt passed through a perforation in the plates D and the web of the rail in the usual manner.

F is the head of the bolt-bearing against one of the plates D; in this instance with an interposed plate G resting upon the foot of the rail, and provided with a lug or shoulder a for one of the faces of the head of the bolt to rest upon to prevent the turning of the bolt. The opposite projecting threaded end of the bolt has screwed upon it the usual

clamping-nut H, and interposed between said nut and the adjacent plate D is what I denominate a "non-rotatable" dog-carrier I, which in this instance is a plate with a perforation for the passage of the bolt and which has feet b resting upon the foot of the rail to prevent the turning of the plate. This provision of feet, however, is simply for the purpose of lightening the weight of the plate, for it might be solid at its bottom, with one continued bearing upon the foot of the rail to prevent the turning of the plate.

Suitably journaled in the plate I and preferably at its inner side is a gravitating dog J, which in this instance is provided with trunnions p, confined in lateral recesses upon the rear face of the plate I. This dog projects through a vertical slot or opening e, whose bottom wall arrests the downward movement of the dog, as seen by the dotted lines, Fig. 1, and the length of the slot is such that the dog can be turned up completely within the plate, as also shown by the dotted lines in Fig. 1, where it can be held by a match or pin inserted in an elongation d of one of the trunnion-recesses. The lower edge of the dog next to the nut is beveled off, as seen at e, Fig. 2, and the location of the dog is such that when one of the sides of the nut stands vertical, as in Fig. 2, the projecting flat side of the dog rests snugly against said side of the nut and effectually locks the same against backward turning, as will be readily seen and understood, though in screwing the nut up the angles of the sides will take under the beveled portion e of the dogs and lift it out of the way to permit the nut to be screwed tightly to place, and then when the side of the nut adjacent to the dog is brought to a vertical position the dog will drop out by gravity and will engage with the side of the nut to lock it in place.

Whenever it is desired to unscrew the nut, it is only necessary to lift the dog and hold it up within the plate I, as indicated by the dotted lines in Fig. 1, whereupon the nut can be readily unscrewed.

By the foregoing simple means I have provided a nut-lock which is thoroughly efficient and not liable to be broken or to get out of order and at the same time it is very simple and cheap in its construction.

Having thus fully described my invention, I claim—

1. In nut-lock construction, the combination of a skeleton-dog carrier provided with legs to prevent its rotation when slipped to place over the threaded end of the bolt, a gravitating dog pivoted to one side of said carrier in the rear wall thereof, a cavity in said carrier terminating in a slot to permit the dog to be projected from the front wall of the carrier against the side wall of the nut screwed upon the end of the bolt and bearing against the carrier to lock the nut from turning, and an opening in the edge of said carrier adjacent to the dog to permit the introduction of a pin for holding the dog up when raised within the carrier, substantially as described.

2. In nut-lock construction, the combination of adjoining ends of the rails, fish-plates embracing the rails on both sides of the joint, bolts uniting said fish-plates and rails, a separate dog-carrier for each bolt upon the threaded end of the bolt and bearing against the adjacent fish-plate and resting upon the foot of the rail, a nut screwed upon the projecting end of the bolt and bearing against the dog-carrier, and a gravitating dog J pivoted in a vertical opening through said carrier, said dog having its under edge adjacent to the nut beveled off, substantially as described.

FRANK C. ANDERSON.
